UNITED STATES PATENT OFFICE.

JEAN BAPTISTE DUREUPT, OF JEUXKEY, NEAR EPINAL, FRANCE, ASSIGNOR TO SOCIETE PELLAUMAIL-MOUTEL & CIE., OF CHOLET, FRANCE.

MACHINE FOR DRAWING OUT THE YARN FROM TEXTILE FABRICS FOR THE PRODUCTION OF OPENWORK.

Application filed March 26, 1925, Serial No. 18,459, and in France October 13, 1924.

The present invention relates to a machine for drawing out the yarn from textile fabrics, comprising in principle two blades which are attached together and are mounted 5 one behind the other, said blades being given a vertical reciprocating motion after the manner of the needles of a sewing machine, one of the blades serving to cut a certain number of parallel threads—of the warp or 10 woof according to the position of the fabric—the second blade serving to drive out the sections of yarn cut by the first blade, the fabric being moved forward by an amount equal to double the distance between 15 the said blades, whereby the pushing blade will act upon the middle of each section of the yarn which has been cut.

In order that the cutting and pushing operations may be effected in favourable 20 conditions, it is necessary that the fabric shall be well stretched during the insertion of the blades and for this purpose the machine comprises the following features:

Firstly, the fabric is given a certain tension during its forward motion, by means of 25 a claw fork which is disposed below the machine table and whose branches are separated during the forward motion of the said fork, the claws of the same drawing forward the 30 fabric by seizing it between two movable plates of a special presser foot.

Secondly, a gripping device assures a strong tension upon the fabric and lowers 35 it against a stationary frame resembling a hand embroidery frame.

Lastly, the apparatus comprises additional features such as a guide for the proper engagement of the fabric below the 40 said blades, and a clearing device for the removal of the sections of yarn which may adhere to the pushing blade before its removal from the fabric.

The following description with reference 45 to the appended drawings which are given by way of example sets forth the said invention.

Figs. 1 to 4 are diagrammatic views showing the method of drawing the yarn.

Fig. 5 is a vertical section of the device 50 for drawing the yarn, which is mounted upon the table of a sewing machine of a known type.

Fig. 6 is a plan view of the machine table, with the mechanism below the table removed.

Fig. 7 is a section on the line X—X of 55 Fig. 6.

Figs. 8 and 9 are detail views, in vertical section and in plan, of the lower gripping device.

Figs. 10 and 11 are elevational and plan 60 views of the upper gripping device forming the presser foot.

Fig. 12 is a section on the line Y—Y of Fig. 11.

Fig. 13 is a view of the lower part of 65 Fig. 12.

Fig. 14 is a front view of the two blades when separated.

Fig. 15 is a view of said blades on a 70 larger scale.

Fig. 16 is a partial side view of Fig. 13 on a larger scale.

Fig. 17 is a vertical section of the combination of the two blades.

Figs. 18 and 19 are detail views showing 75 two different positions of the clearing device serving for the removal of the yarn which may adhere to the pushing blade when it ascends.

Figs. 20, 21, 22, 23 are diagrammatic sec- 80 tional views showing the operation of the claws and the gripping devices.

Figs. 20^a and 23^a are sections on the lines Z—Z and Y—Y of Figs. 20 and 21.

Figs. 20^b and 21^b are plan views of Figs. 85 20 and 21.

The principle of the yarn-drawing machine, the object of the invention, will be set forth with reference to the diagrammatic Figures 1 to 4 in which the different 90 warp and woof yarns are spread out for the sake of clearness.

The fabric which is disposed as shown in cross section and in plan view in Figs. 1 and 3, moves forward in the direction of the arrow 2. A set of two blades is displaced perpendicularly to the fabric whereof one blade 3 has a cutting edge and acts as a cutting blade and the second blade 4 has a corrugated or hooked edge and acts as a pushing blade. The set of the two blades is given a vertical reciprocating motion after the manner of a sewing machine needle.

The said machine is so regulated that 105 each forward movement of the fabric is equal to double the spacing *i* of the said blades. At each descent of the said device, the blade 3 will cut a certain number of

threads 1 of the fabric while leaving intact the woof yarn 1^a said blade or needle 3 will thus cut out a certain number of elements or sections of yarn 1^b, and upon each descent 5 of the set of blades the yarn will be pushed down by the blade or needle 4, which as shown in Figs. 1 and 2 will exercise a downward thrust upon the middle of the elements 1^b which have just been cut.

10 The two assembled blades, Fig. 17, are mounted by means of a tapered shank, or in like manner, in the support 5 of a sewing machine, and are given a vertical reciprocating motion by the mechanism of the machine. 15 In the place of the known presser foot, there is secured to the end of the usual rod 6, Fig. 5, the upper branch 7 of the gripping device which is shown in detail in Figs. 11, 12 and 13, and comprises a central striated plate 8 having at the middle part a large aperture 8^a; to the sides of the said plate are pivoted the respective shoes 9 which have a certain play in order to move freely on their axis 11 and also to ascend to a slight degree; they 20 are maintained in the lower position by a small spring 12. To the plate 8 is secured the arm 13 which serves to guide the fabric.

Below the table of the sewing machine is disposed the mechanism providing for the 25 tension and for the forward motion of the fabric. The said mechanism comprises the lower branch of the gripping device which is constituted by the striated plate 16 situated opposite the plate 8 of the upper branch 7; the plate 16 rests through the medium of four small springs 17 upon a stationary plate 18 having two parallel flanged edges 18^a (Figs. 20^a and 23^a) forming the parallel sides of a frame upon which the fabric is stretched as will be hereinafter set forth. The flanges 18^a engage a rectangular slot 16^a in the plate 16, which can thus slide vertically on the said flanges. 40

The plate 18 has two lateral holes 20 affording passage for two respective claws 21, when the latter are raised; the said claws, which move at the same time, are actuated by a suitable mechanism which raises them in such manner as to press the fabric between them and the shoe 9. At this time the claws move forward and are at the same time separated from each other in order to provide for the forward motion of the fabric while stretching the latter, and then descend in order to allow the plates or clamps 50 8 and 16 to energetically stretch the fabric upon the parallel edges 18^a, after the manner of an embroidery frame.

The operation is as follows: The claws 21 are provided at the end of suitable arms 22 which form the two branches of a fork, this being pivoted (with some play) on the axis 23 at the end of a lever 24 mounted on a shaft 25; this latter is given an angular reciprocating motion by means consisting of 65

the lever 26, the link 27, and the bent lever 28 pivoting on the axle 28^a, whose forked end is controlled by a cam 29 mounted on the shaft 30 of the sewing machine (Figs. 6 and 7). Below each arm 22 is mounted a reaction 70 spring 31 attached to a fixed point 32 of the machine frame.

The forward ends 22^a of the levers 22 carrying the claws 21 rest upon tappets 33 formed by the rear ends of the fork 33^a pivoting at 34, which are given a reciprocating motion by the cam 36 acting on the fork 37 mounted at the end of the shaft 34, which latter turns in two bearings mounted on the machine. The tappets 33 comprise the vertical extensions 38 in friction contact with the inner faces of the claws 21; said extensions (Figs. 20^b and 21^b) have an external face in the inclined position in order to spread apart the two claws 21 as they move 80 forward. A spring 40 (Fig. 20^b) urges the said claws 21 together.

The operation of the machine is as follows:

The branch 7 of the gripping or clamping device which acts as the presser foot being raised in the usual manner, the fabric is placed between the plates 8 and 16 when the same are in the raised position. The presser foot is then lowered. The several parts of the machine are now in the position shown in Figs. 20 and 20^a. The fabric is held between the claws 21, which are now in the raised position, and the shoes 9; at this time, the claws 21 move forward in the direction of the arrows Fig. 20, sliding upon the tappet 33 which remains stationary. In this motion the said claws will open out, while sliding upon the said faces, thus affording the suitable tension of the fabric; the opening of the said claws is made possible by the play provided for the axis 23. This opening of the said claws will be observed in Figs. 20^b and 21^b, which correspond to the beginning and the end of the opening movement. 100

The claws 21 then descend, and the presser foot, which is held in the raised position by the said claws will follow this movement and will descend thereupon under the action of a spring (not shown) which urges the presser foot downwardly; in this downward motion of the presser foot, the plate 8 which is secured thereto will press the fabric, which has been preliminarily stretched by the claws 21, against the plate 16 (Fig. 23^a). When in this position, it will be observed that the fabric is stretched upon the parallel edges 120 18^a of the stationary plate 18, this tension being analogous to what takes place in an 125 embroidery frame.

The mechanism is so combined that the fabric will be held between the plates 18 and 16 at or somewhat before the moment at which the claws 21 leave the fabric. 130

As above stated, the claws 21 can be lowered by reason of the descent of the tappet 33 which moves from the position shown in Fig. 21 into that shown in Fig. 22, the said claws being lowered in virtue of the traction exercised by the spring 31 below the said claws.

The claws 21 having assumed their extreme position, Fig. 22, they are then brought back by a sliding motion upon the tappet 33 which remains stationary, until they attain the position shown in Fig. 23, and the cycle of operations is continued in the same manner.

15 The double blade or needle is inserted into the fabric while the latter is stretched upon the parallel edges 18^a (Figs. 22 and 23); when the set of blades has been withdrawn from the fabric the claws 21 cause the fabric to move forward while stretching the same, this motion being exactly equal to double the distance between the said blades. This forward motion may be regulated as in the known machines, for instance by 25 changing the length of the lever arm 28^a 28^b. For this purpose the bent extension 28^c of the fork 28 forms a guide, and the axis 28^b can be moved therein by a micrometric screw mechanism or the like.

30 The said machine, the object of the invention, comprises a special device termed "clearing device" which serves for the removal of the cut ends of yarn which may remain attached to the rough edges of the 35 pushing blade 4; said device which is shown in plan view in Figs. 18 and 19 consists of a plate 45 which is slidable below the plate 18 to which it is attached by the pin 46 engaging the slot 47 in the plate 45.

40 The curved end 45^a of the plate 45 is held in an elastic manner between two spiral springs 48, 49 surrounding the rod 50 whose end 50^a is pivoted to the axis 50^b mounted between the branches 22 of the claws 21, as 45 shown in Fig. 6. In the sliding plate 45 is formed a slot 51 in which is engaged the stationary plate 52 apertured at 53 for the insertion of the blade or needle 3, and the same constitutes an edge 54 which comes 50 between the blades 3 and 4 when they rise and descend, Fig. 18.

The said clearing device operates in the following manner, Figs. 18 and 19.

55 When the said double blade is driven into the fabric, the plate 45 will be situated at extreme left, Fig. 19, and there will be a space between the edge 54 of the plate 52 and the edge 45^a of the plate 45; the driving blade 4 moves in this space. Upon the 60 ascent of the blades, the claws 21 will move back, as above stated, and will draw back (through the medium of the spring 48) the

plate 45 in the direction of the arrow, Fig. 19. The edge 45^a enters into elastic contact with one face of the driving blade 4 whose other face is in contact with the edge 54 of the plate 52. The combination of the two edges 45^a and 54 will arrest the yarn which has become caught in the toothed part of the blade 4 when the latter rises.

70 When the said blades or needles become disengaged from the fabric, the claw device 21 moves forward, drawing with it (through the medium of the spring 49) the plate 45 in the direction of the arrow, Fig. 18, and the latter will spread apart the edges 54 and 45^a and thus bring the elements into the position of Fig. 19.

Obviously, the said device is susceptible of various modifications without departing 80 from the principle of the invention; in particular, it may comprise a set of blades 3 and 4 having different widths according to the height of the open work which is to be formed in the said fabric.

85 What I claim is:—

1. In a machine for drawing out yarn from textile fabric for the production of open work, a stationary frame to receive the fabric, claws having serrated faces to seize the fabric, means for separating the claws and for moving them forward simultaneously to stretch the fabric, means for lowering the stretched fabric onto the frame, a cutting blade for severing threads of the fabric, a toothed blade for engaging the severed threads, means to reciprocate the blades through the fabric, a fixed plate and a movable plate mounted below the fabric frame and having cooperating flanges 95 formed thereon, and resilient means for actuating the movable plate to bring said flanges into contact with the toothed blade to arrest the threads attached to the latter.

100 2. In a machine for drawing out yarn from textile fabrics for the production of open-work, a holder, a cutting blade and a toothed blade carried by the latter, claws adapted to seize the fabric, means for imparting a simultaneous forward and outward movement to said claws for the lateral tension of the fabric, pairs of grips, means whereby said pairs of grips will seize the fabric preliminarily stretched by the claws while said claws are withdrawn therefrom,

105 stationary parallel vertical plates, means for lowering the said grips to additionally stretch the fabric over the edges of said plates, and means for moving the blades through the fabric.

110 115 120 In testimony whereof I have signed this specification.

JEAN BAPTISTE DURUPT.
